United States Patent Office.

JOSEPH BRAUN, OF BRIDGEWATER, PENNSYLVANIA.

Letters Patent No. 69,171, dated September 24, 1867.

IMPROVED DRIER FOR SCOURED CLOTHES.

The Schedule referred to in these Letters Patent and making part of the same.

TO ALL WHOM IT MAY CONCERN:

Be it known that I, JOSEPH BRAUN, of Bridgewater, in the county of Beaver, and State of Pennsylvania, have invented a new and useful Improvement in Drying Wearing Apparel that have been subjected to the scouring process; and I do hereby declare that the following is a full, clear, and exact description thereof, reference being had to the accompanying drawings, and to the letters of reference marked thereon.

The nature of my invention consists in the use of a hollow metallic core, the form of which corresponds to the form of that part of the human body to which the garment is adapted, said metallic core being suitably supplied with steam, and constructed, arranged, and operating in the manner substantially as hereinafter described.

To enable others skilled in the art to make and use my invention, I will proceed to describe its construction and operation.

In the accompanying drawings, which form part of my specification—

Figure 1 represents a front elevation of the hollow metallic core used for the purpose of drying coats and upper garments.

Figure 2 represents a front elevation of the hollow metallic core used for the purpose of drying pants and other lower garments.

In the drawings A represents that part of the metallic core which is used for drying that portion of the coat or vest which covers the upper part of the human form. B represents the part of the core A which is used for drying the skirts of the coat. The part B of the core A is so arranged that a thin sheet of steam will be used in drying the skirts of the coat, while a large body of steam will be used for drying the body of the coat. The narrow space for steam in the hollow metallic core A is represented by the dotted lines marked X', shown in fig. 1. C represents the core used for drying the sleeves of the coat. These sleeve-cores are held to the main core A by means of hooks O, but other means may be used for securing them to the main core A. The steam-chambers of the cores C should always communicate with the steam-chamber of the main core A. On the lower end of the sleeve-cores C are placed small pipes, f, for conducting off the water which is formed by the condensation of the steam. To these pipes f may be attached cores, for drying stockings or gloves. h represents the neck or collar-core. D represents the hollow metallic core for drying the pants, the legs e of which are provided with pipes 1 and 4. On each side of the core D are hollow expanders, marked m, which are held in the desired position, with relation to the core D, by means of pins S. The expanders m are provided with springs, marked 2, which are used for the purpose of holding the expanders m out from the core D. These expanders are used for adapting the core to the various size of pants. On the lower ends of the expanders are pipes 3 and 5. The pipe 3 is fitted over the pipe 1 on the lower ends of the legs e, so as to form a steam-tight joint and allow the expanders to move freely out from or in towards the core D. The small pipes 5 on the lower end of the expanders are used for conveying off the water formed by the condensation of the steam. g represents a pipe, which is fitted to the opening represented by dotted lines, and marked X in fig. 1. It will be observed that when the core D is connected to the core A, by means of the pipe g and opening X, the upper portion of the core D will be surrounded by the part marked B of the core A, and the cores A and D will be so arranged with relation to each other that a steam communication is formed between them.

The skillful mechanic will readily understand that the core A and its sleeve-cores C can easily be provided with expanders similar to those on core D, shown in fig. 1, and thereby adapt the core A and its sleeve-cores to coats and upper garments of different sizes. And it will also be readily understood that the cores A and D can be used separately, by suitably connecting them by means of pipes to suitable steam-vessels.

In constructing my improved drier care should be taken to have all the joints and connections of the pipes steam-tight, and it will also be found that sheet copper is the most suitable metal for constructing it, but any other suitable material may be used. The mode or manner of constructing I leave to the skill and good judgment of the mechanic.

As the construction of my improved drier will readily be understood from the foregoing description, and by reference to the accompanying drawings, I will, without further description of its construction, proceed to describe its operation, which is as follows:

Having all things constructed and arranged as herein described and represented, I scour the wearing apparel

in the usual manner and ring or press out the water. I then draw the pants over the core D and properly fit the pants to the core, and having them sufficiently stretched and made smooth I secure them to the core by means of cords or tape. In placing the coat or vest on the core A I remove one of the cores C for the sleeves. I then put the other sleeve-core in one of the sleeves of the coat (or in the arm-hole of the vest.) I then place the other sleeve-core in the other sleeve of the coat, and then secure the removed core to its place on the main core A. I then draw and fit the coat (or vest) to the core, and secure it by means of cords or tapes to its place on the core. I then place the pipe g of the core D in the opening X of the core A. I then attach the pipes 4 to a suitable steam-vessel, and admit steam into the core D. From it steam will pass through pipes 1 and 3 into the expanders m, and through pipe g into the core A and its different parts. The steam thus admitted into the cores will dry the clothes. The speed of drying will in every case depend on the heat of the steam or pressure of steam in the cores.

Among the many advantages of my improved drier are the following: The clothes are quickly dried without injury to the cloth or its color; it gives to the cloth a bright and new finish, and the shrinkage of the clothes is entirely avoided.

By the use of a metallic core made in the form herein described, and provided with a large number of very small openings for the outlet of steam, clothing may be cleansed and purified in the most perfect manner. But I propose making this a future subject for Letters Patent, and shall not therefore give further description of the device.

Having thus described the nature, construction, operation, and advantages of my improvement, what I claim as of my invention, is—

The use of a hollow metallic core, the form of which corresponds to the form of the human body and its wearing apparel, said metallic core being used with steam, substantially as herein described and for the purpose set forth.

JOSEPH BRAUN.
